UNITED STATES PATENT OFFICE.

HERBERT GUETTLER, OF CHICAGO, ILLINOIS, AND WILLIAM LLYWELYN DAVIS, OF
EAU CLAIRE, WISCONSIN.

BARKING-DRUM.

1,272,945.

Specification of Letters Patent. Patented July 16, 1918.

Application filed May 2, 1916, Serial No. 94,913. Renewed May 29, 1918. Serial No. 237,365.

To all whom it may concern:

Be it known that we, HERBERT GUETTLER, a subject of King Hakon VII of Norway, residing in Chicago, county of Cook, State 5 of Illinois, and WILLIAM LLYWELYN DAVIS, a citizen of the United States, residing in Eau Claire, county of Eau Claire, Wis., have invented certain new and useful Improvements in Barking-Drums; and we do hereby 10 declare the following to be a full, clear, and exact description of the invention, such as will enable others skilled in the art to which it appertains to make and use the same.

It is possible to remove bark from logs or 15 blocks of wood preparatory to use of the wood in the paper making industry by tumbling the logs or blocks in a rotating drum which preferably is partially immersed in water held in a suitable tank. The drum 20 may be so constructed as to have a plurality of longitudinal slots through which the bark may escape from the drum into the tank, and the wood may be fed continuously into one end of the drum and discharged continu- 25 ously from its other end, while the drum is in motion.

It is the object of the present invention to provide a wood barking drum of special construction and so arranged as to facilitate the 30 discharge from the drum of the logs or blocks, and more particularly, the large logs or blocks.

It has been found that in the operation of continuously rotating drums of the type 35 above described, that the larger and heavier logs or blocks have a tendency to stay near the bottom of the cascading pile of wood within the drum, and so are liable to be tumbled longer than is necessary with re- 40 sultant reduction in the output of the drum, and with possible danger of unduly shattering the ends of these large pieces or blocks.

To accomplish the foregoing object, and others which will be made clear by the fol- 45 lowing description, the cylindrical wall of the drum is built up out of bars, strips, or the like, which are mounted within and secured to supporting rings, and which at the discharge end of the drum, have a back- 50 ward curve which gives to the logs or blocks a thrust toward the outlet and so facilitates their discharge and prevents the accumula- 55 tion of large and completely treated blocks at the outlet end of the drum and near the bottom of the tumbling pile.

The details of the invention are made clear by the following description, which is to be taken in conjunction with the accompanying drawings, wherein—

Figure 1 is a side elevation of a drum 60 mounted for rotation in a tank of water;

Fig. 2 is a sectional elevation on the line 2—2 of Fig. 1;

Fig. 3 is an elevation of the discharge end 65 of the drum;

Fig. 4 is a side elevation of the discharge end of the drum; and

Fig. 5 is a fragmentary section through the drum.

In the embodiment illustrated, the tank 1 70 is of concrete with a semi-cylindrical chamber for holding water and with an adjustable dam 2 formed by removable flash boards fitted into grooves in the cement tank and regulating the level of the water. A frame- 75 work 3 mounted on the tank carries a drive shaft 4 and countershafts 5 provided with a sprocket wheel 6 and a smooth wheel 7, respectively, over which are passed driving and supporting chains 8 of which three may 80 be used for sustaining the drum in the tank substantially concentric with the body of water contained therein. The countershafts 5 may be mounted in sliding bearing blocks, as illustrated, to equalize the tension on the 85 chains.

At the intake end of the drum is a chute 9 leading from a conveyer 10, and down which wood may be delivered to the drum during its rotation. At the discharge end 90 of the drum, a plurality of planks 11 are removably mounted in guideways formed in the end members of framework 3, as indicated in dotted lines, Fig. 1, and serve to partially close the discharge end of the 95 drum. The height of the wood pile within the drum may be regulated by the number of planks 11 which are in position in the guideway. The drum itself comprises a plurality of flanged rings 12 and a plurality 100 of smooth rings 13 (Fig. 4) over which the three driving and supporting chains 8 may pass, and a pair of guide-rings 14 (Fig. 1) which are embraced by flanged guide-rollers 15 (Fig. 2) to prevent the drum from swing- 105 ing or jumping in the tank.

The cylindrical wall of the drum is made up of a plurality of bars 16, which, as shown in Fig. 5, may be in the form of angle bars or channels or T-bars, or a combination of 110

these three forms, and the bars are spaced apart to form longitudinal bark discharging slots 17 through which the bark, loosened from the blocks or logs, when they are tumbled within the drum, may find exit into the water of the tank where it is progressively swept out over dam 2 by means of fork-shaped paddles 18 attached to the periphery of the drum.

10 Throughout the greater part of their length, the bars 16 may be straight, but near the discharge end of the drum, they are curved backward with reference to their direction of rotation, and it is this backward curvature that is relied on to effect prompt and complete discharge of thoroughly barked blocks and logs, and more particularly, the heavy pieces, which might otherwise, because of their weight, be entrapped for a time at 20 the end of the drum.

When the drum is in action, it receives wood continuously from chute 9 and delivers it continuously over the barrier formed of planks 11 and down a chute 19 to an endless 25 conveyer 20, by which it is taken away for further treatment. The operation is continuous for the bark delivered through the slots is progressively and continuously swept out of the tank, and over dam 2, by means of 30 the paddles 18 with which the drum is provided. The speed with which the pieces of wood travel through the drum can be regulated by changing the height of the barrier at the discharge end of the drum. Rail 35 wood should be tumbled longer than wood that has had its bark loosened by prolonged immersion in water, and some species of wood are more easily barked than others. The barking action results mainly from the sliding of the blocks on one another as the pile of wood is caused to cascade within the drum through action thereon of the inwardly projecting flanges of the bars constituting the cylindrical wall of the drum. The 40 blocks move progressively and slowly toward the discharge end, and as soon as they come under the action of the backwardly curved flanges, they are given an additional thrust longitudinally of the drum, and their 45 delivery over the barrier is thereby facilitated, and there is little or no tendency for the larger and heavier pieces to accumulate 50 against the barrier, as has proved the case

when the flanges on the bars do not have the backward bend or curve here contemplated. 55

We claim:

1. A barking drum having longitudinal bars with spaces between forming slots for the escape of bark, said bars being bent backward near the discharge end of the drum to 60 facilitate discharge of wood therefrom.

2. A barking drum comprising rings connected by bars with spaces therebetween through which bark may escape, said bars having a backward curve near the discharge 65 end of the drum to facilitate discharge of wood therefrom.

3. A barking drum comprising rings connected by bars having flanges with slots between the bars through which bark may 70 escape, the flanges of said bars extending inward to cascade the wood to be barked, said flanges having a backward bend near the discharge end of the drum to facilitate the delivery 75 therefrom of the barked wood.

4. A barking apparatus comprising a drum, a tank in which said drum may rotate partly immersed in water, means for continuously rotating said drum while wood is being fed into the intake end thereof, a barrier retarding the delivery of wood from said drum and baffles within said drum to tumble the wood therein, said baffles having a backward curve near the discharge end of the drum to facilitate delivery of wood 85 therefrom over said barrier.

5. A barking apparatus comprising a drum, a tank in which said drum may rotate partly immersed in water, means for continuously rotating said drum while wood to 90 be barked is being fed into the intake end thereof, said drum comprising rings connected by bars which have flanges extending inward to form baffles for tumbling the wood as the drum rotates, said flanges extending parallel to the axis of the drum except near its outlet end where they are curved backward to facilitate the delivery of wood from the drum, and a barrier partially closing the discharge end of the drum and 100 over which the wood is discharged, substantially as described.

In testimony whereof we have hereto affixed our signatures.

HERBERT GUETTLER.

WILLIAM LLYWELYN DAVIS.
